UNITED STATES PATENT OFFICE

GUSTAV EGLOFF, OF INDEPENDENCE, KANSAS, ASSIGNOR TO UNIVERSAL OIL PRODUCTS COMPANY, OF CHICAGO, ILLINOIS, A CORPORATION OF SOUTH DAKOTA

PROCESS AND APPARATUS FOR CRACKING OIL

Application filed December 6, 1920, Serial No. 428,788. Renewed February 7, 1930.

This invention relates to improvements in process and apparatus for cracking oil, and refers more particularly and has among its objects the cracking of fuel oil in one heating chamber and reflux condensate obtained by condensing the vapors generated from the raw oil in another heating chamber, while subjecting part of the apparatus to a vacuum action. The invention also relates to the cracking of fuel oil or other heavy oils in one heating chamber, and reflux condensate mixed with a lighter raw oil, as for example gas oil, in another heating chamber. The invention also relates to the cracking of fuel oil in one heating chamber and gas oil or fuel oil in another heating chamber, while the reflux condensate may be diverted to either chamber or carried elsewhere for treatment. In any event, the oil in the separate chambers may be subjected to different conditions of heat and pressure. It is well known to those skilled in the art that different cuts of petroleum oil are desirably cracked under different conditions of heat and pressure. It is also well known that most of the cracked gasoline now in the market is a blended material. This blending is done after the pressure distillate has been produced, as for example, by mixing the gasoline obtained from the pressure distillate with casinghead gasoline or gasoline obtained from fractional distillation of crude or both. In the present invention, this blending is accomplished as part of the cracking operation, thus being able to obtain a much more effective and cheaper blend than might otherwise be possible.

In the drawing, the single figure designates a view partly in vertical section and partly in side elevation of my improved apparatus. Referring to the drawing, 1 designates a furnace, provided with upper and lower combustion chambers 2 and 3, and corresponding burners 4' and 4, the combustion chambers being separated by a foraminated bridge wall 5. The furnace is, of course, equipped with the usual stack 6. In the combustion chamber 2 is seated a heating chamber 7, which may take the form of a continuous coil of four-inch pipe, say 200 to 600 feet long. In the lower chamber 3 is

mounted a similar pipe 8 which may be of the same diameter and length. The diameter and length of the pipes will be determined somewhat by how much oil is to be fed into one heating chamber relative to the other. The heating coil 7 is provided with feed line 9, having throttle valve 10, connected to the delivery side of pump 11, which pump 11 is connected at its inlet side by line 12, having throttle valve 13, to any suitable source of raw oil supply, as for example, gas oil or kerosene. The inlet side of the coil 8 is connected by feed line 14, having throttle valve 15, to charging pump 16. This pump 16 is connected at its inlet side to the raw oil line 17, having throttle valve 18, which line 17 may be connected to supply of fuel oil or such heavy oils as asphaltic, Mexican or California asphaltic crudes or mid-continent heavy crudes or heavy fuel oils. The delivery sides of the coils 7 and 8 are connected by transfer lines 19 and 20, having throttle valves 21 and 22, to a main transfer line 23, having throttle valve 24'. The line 23 connects to a large shell-like expansion chamber 24, which chamber 24 is provided with residue draw off pipe 25, having throttle valve 26. To the upper part of the chamber 24 is connected a vapor outlet pipe 27, having throttle valve 28, which pipe 27 leads to a dephlegmator 29. This dephlegmator 29 is provided with suitable baffle members 30, and at its upper end is connected by vapor outlet line 31, having throttle valve 32, to condenser coil 33, seated in condenser box 34. The coil 33 is connected at its lower end by pipe 35, having throttle valve 36, to the top of receiver 37. This receiver 37 is provided with liquid level gauge 38, liquid draw off pipe 39, having throttle valve 40. It also has gas outlet pipe 41, having throttle valve 42 and extension 41', leading to vacuum pump 43. A branch pipe 44, having throttle valve 45, is also provided. The arrangement is such that a vacuum may be maintained on the condensing part of the apparatus, or by shutting the valve 42 and regulating the valve 45, a pressure may be maintained on the condensing part of the system. The heavier vapors which are condensed 100

in the dephlegmator are drawn off from the lower end of the latter through the reflux pipe 46. This pipe 46 is provided with a branch 47, having throttle valve 48, which branch 47 is connected to the pump 11. It also has a branch 49, having throttle valve 50, which branch 49 leads to the inlet side of the pump 16. It is also provided with still another branch 51, having throttle valve 52, leading to any suitable receptacle (not shown). The arrangement is such that the reflux condensate may be returned to either of the heating coils or may be diverted elsewhere. The system is provided with suitable pyrometers (not shown), and with a plurality of pressure gauges 53.

A process may be carried out in this apparatus as follows:

Fuel oil of a more or less asphaltic nature of say 26 degrees Baumé may be fed continuously to the heating coil 8, and there heated to a temperature of say 675 degrees F., and subjected to a pressure of say 100 pounds. It is delivered into expansion chamber 24, preferably in substantially liquid phase so as to prevent precipitation of carbon in the coil. At the same time gas oil of say 32 degrees Baumé may be fed continuously through the second heating coil 7, and there subjected to a temperature of say 750 degrees F. and a pressure of say 150 pounds. It also is delivered in substantially liquid condition for the same reason to the expansion chamber. Here vaporization of the mixture takes place, and the vapors pass to the dephlegmator. The heavier or incompletely converted portions thereof will be condensed and drawn off through the reflux line. If this reflux condensate is particularly refractory, or of a gravity of substantially the same as the gas oil, it should be returned to the heating coil 7. On the other hand, if it more nearly approaches the character of the fuel oil, it should be returned to the lower coil 8. In certain cases, it may be desirable to divert this reflux condensate elsewhere and separately crack it. The expansion chamber, dephlegmator and condenser and receiver may be all maintained under a pressure of say 90 pounds. The process may be carried out by maintaining the dephlegmator and condenser and receiver under a vacuum, while the pressure remains as before on the remainder of the system. If desired, a vacuum may be maintained even on the expansion chamber. By means of this process, some 60% of the raw oil supply may be converted into pressure distillate of say 53 degrees Baumé gravity, containing some 30% to 40% of 400 end point gasoline based on the raw oil charge.

A process may be carried out in this apparatus, in which the raw oil in the lower coil may be fuel oil or a mixture of fuel oil and gas oil, and the raw oil in the upper part kero-

sene or a mixture of kerosene and gas oil, and the reflux condensate may be carried through any one of the three branches heretofore described. In any event, the process will be so operated as to secure in the final product a 70 gasolene or other like oil content containing the relative proportions of the various end point cuts. For example, in cracking the fuel oil, the gasolene produced therefrom may be say 56 degrees Baumé gravity, while the gasolene produced from cracking the kerosene or gas oil might be 58 degrees Baumé gravity. By suitably regulating the amount obtained from each raw oil, it will be seen that a blend of the desired character may be obtained. 75 For example, it might be desirable to contain in the blend some so-called "wild" gasolene, which may be obtained by cracking in the upper coil kerosene to form very light cuts, for example, those having an end point of 80 70 to 100° F.

I claim as my invention:

1. An apparatus for cracking oil, the combination of a furnace provided with two superimposed interconnected combustion chambers, a coil seated in one chamber for receiving an oil of predetermined gravity, a coil seated in the other chamber for receiving an oil of a different gravity and an expansion chamber to which both coils are connected, a reflux condenser connected with the vapor space of the expansion chamber, and connections between the lower part of the reflux condenser and each of the coils. 90

2. In an apparatus for cracking oil, the combination with a plurality of heating chambers, of a heating coil positioned in each of said heating chambers, means for supplying oils from separate sources to the different coils, an enlarged expansion chamber to which said plurality of coils are connected, a reflux condenser connected with the expansion chamber, means for returning reflux condensate from the reflux condenser selectively to any one of said plurality of coils, and means for removing the reflux condensate from the apparatus in the event that it is not desired to return the reflux condensate to any one of said coils. 105

3. A method of cracking a mineral oil 115 which comprises: heating a stream of a heat-transferring medium while out of contact with said mineral oil to a temperature above the temperature at which said mineral oil may be cracked; advancing said stream of heat-transferring medium while so heated into direct contact with a separately advancing stream of said mineral oil, to heat the latter during its advance and without subsequent application of external heat; separating resultant vapors from the residue fractionating the vapors; and employing at least a portion of bottoms from the vapor fractionation as said heat-transferring medium. 120
